SEWING ACCESSORY

Robert Solomon, New York, N. Y.

Application January 31, 1955, Serial No. 34,307

Term of patent 3½ years

(Cl. D3—19)

Fig. 1 is a front elevational view of a sewing accessory showing my new design.

Fig. 2 is a side elevational view.

The appearance of the back of the design is identical with the appearance of the front of the design which is shown.

I claim:

The ornamental design for a sewing accessory, substantially as shown and described.
